UNITED STATES PATENT OFFICE.

HENRY ANTONY MEIKRANTZ, OF OLIVERS MILLS, PENNSYLVANIA.

LOCK-SHOE.

No. 852,888.

Specification of Letters Patent.

Patented May 7, 1907.

Application filed February 13, 1907. Serial No. 357,218.

To all whom it may concern:

Be it known that I, HENRY ANTONY MEIKRANTZ, residing at Laurel Run, Olivers Mills, in the county of Luzerne and State of Pennsylvania, have invented a new and Improved Lock-Shoe, of which the following is a specification.

This invention relates to improvements in that type of lock shoes or brakes adapted for application to vehicle wheels, bob sleds, etc., for locking them while moving or sliding down inclines or over slippery places, and which are especially provided for preventing vehicles from sliding too fast, forward or 15 sidewise, on lateral inclines or ice covered road ways, and by means of which the vehicle wheels can be locked or released, as desired.

My invention, in its generic nature, comprehends an improved construction of appliance, of the character stated, in the nature of a "goose neck rough lock" having means for interchangeably holding the different drag shoes or plates designed for winter or 25 summer use, and in which the several parts have such designs and correlation whereby the entire appliance can be economically and conveniently made up in an ordinarily equipped blacksmith shop, and which can 30 be quickly applied for use and effectively serve for its intended purposes.

In its more specific nature my invention consists in certain details of construction that will hereinafter be fully explained and specifically pointed out in the claims, as well as 35 illustrated in the accompanying drawings, in which:—

Figure 1, is a side elevation of a wagon, showing my invention as applied for use 40 with the "summer equipment." Fig. 2, is a longitudinal section of the shoe end of the appliance and illustrates its application to the wheel, the parts having the engagement shown in Fig. 1. Fig. 3, is a similar view 45 showing the "winter equipment" of my invention. Fig. 4, is a transverse section on the line 4—4 of Fig. 2. Fig. 5, is a similar view on the line 5—5 on Fig. 3. Fig. 6, is a perspective view of the entire appliance with 50 the "summer shoe equipment." Fig. 7, is a longitudinal section of the shoe carrying end of the appliance and illustrates the manner in which the several parts are adjusted to provide for the removal of the winter 55 equipped calks. Fig. 8, is a detail view of the summer brake shoe.

In carrying out my invention, I provide a drag frame, composed of two parallel side members *a—a* having in side view a goose neck shape, the upper ends thereof being 60 joined by a cross piece *b* which may be, and preferably is formed integral with the side members *a—a* and which has a transverse slot *b'* in which plays a draft ring, *c*.

The bottom portion of the members *a—a* 65 are longitudinally extended to form shoe portions *a'—a'* which are aligned with and are integral with a main drag plate or shoe *d'* the front end of which curves upwardly as at *d'* and the said shoe portions *a'—a'* near 70 the front end have apertures *2d—2d'*, as clearly shown in Fig. 4, by reference to which it will be seen that the said apertures *2d—2d'* are adapted to receive a pivot key *e* removably held in the said portions *a'—a'* by the 75 keeper *e'*.

f designates a supplemental shoe or drag plate provided with an apertured and transversely disposed sleeve *f'* at the forward end, for engaging with the pivot key *e* and the 80 front end of the said plate *f* is suitably curved so that the body thereof can be readily fitted over the bottom of the main drag plate when the engaging members or calks of the said plates, presently referred to, are removed. 85

The main drag plate has a transverse slot 10 near its rear end and a longitudinal slot 11 near its front end, the upper ends of both slots being countersunk as at *10a—11a* to receive the inclined flanges *12a* of the front and 90 rear engaging members or calks *12—12* that are removably held in the said slots and are secured in position by a cap plate *13*, the forward end of which has apertured ears *13a* to engage with the front pivot pin or key *e* 95 whereby, by swinging the said cap plate upwardly to the position shown in Fig. 7, the engaging members or calks will be exposed so that they can be readily removed from the main drag plate, the said cap plate *13* being 100 firmly held locked against the top of the main plate when desired, by a keeper pin *14* that passes through the rear ends of the opposite shoe portions *a'—a'* of the members *a—a*. 105

From the foregoing, taken in connection with the drawings, the complete construction and the manner in which my lock shoe operates, together with its advantages, will be readily understood. It will be apparent 110 that by removing the supplemental shoe and applying the engaging members or calks I

provide an effective lock shoe for winter use, since by placing the shoe beneath the wheel that it is to lock, and attaching the draft ring to some forward portion of the vehicle, 5 the goose neck members will hold the shoe from lateral displacement with respect to the wheel. By reason of providing the calks transversely and longitudinally, should there be any tendency to slip or skid on the ice or 10 on the inclines, the engaging members or calks will prevent such movement by removably connecting such calks and providing for detachably securing the smooth faced supplemental drag shoe, the latter, when attached, closes the slots in the main shoe or plate and acts as a smooth shod shoe for use in the summer or on places where ice or very steep inclines are not encountered.

Having thus described my invention, what 20 I claim and desire to secure by Letters Patent, is:—

1. A lock shoe comprising a main drag plate, a plurality of engaging members separably connected with the plate, and a means 25 common to all the engaging members for securing them in place; in combination with a supplemental drag plate adapted to be fitted over the main drag plate when its engaging members are removed.

30 2. A lock shoe comprising a drag frame, and a main drag plate that forms a fixed part of the said drag frame, a supplemental drag plate and means for detachably connecting said supplemental drag plate so it can be 35 fitted over the drag face of the other or main plate, for the purposes described.

3. A lock shoe comprising a drag frame, a main drag plate fixedly connected thereto and engaging members that project from the

faces of the said plate, the said members being removably connected to the plate; in combination with a supplemental drag plate and a means for detachably securing the said supplemental drag plate to the drag frame to fit over the faces of the main drag plate when 45 its engaging members are removed.

4. A lock shoe which comprises a goose neck shaped drag frame constructed to straddle the wheel rim, a main drag plate which forms a fixed part of the drag frame, an engaging member projected from the faces of the main drag plate and removably held upon the said plate, means for holding said engaging member in place on the main drag plate, said means engaging the pivot cap plate, a supplemental drag plate and the single means for pivotally sustaining the supplemental drag plate and the cap plate on the drag frame, substantially as shown and described.

5. The combination with the side members *a—a*, the main drag plate and the engaging members or calks removably mounted on the main drag plate; of the supplemental drag plate, the calk securing cap 65 plate, the said supplemental drag plate and the cap plate having alined apertured ends, a key pin for detachably engaging said apertured ends and the side members *a'*, and the lock pin detachably engaging said side members and adapted to lock the cap plate down against the main drag plate for holding the calks on the said plate, as set forth.

HENRY ANTONY MEIKRANTZ.
